[57] CLAIM

The ornamental design for a lateral anastomosis surgical stapler, substantially as shown and described.

DESCRIPTION

FIG. 1 is a perspective view of a lateral anastomosis surgical stapler showing my new design;

FIG. 2 is a side elevational view thereof;

FIG. 3 is a side elevational view thereof as seen from the rear of FIG. 1;

FIG. 4 is a top plan view thereof;

FIG. 5 is a bottom plan view thereof;

FIG. 6 is an end elevational view thereof as seen from the left of FIG. 2; and

FIG. 7 is an end elevational view thereof as seen from the left of FIG. 3.
